Attorney

UNITED STATES PATENT OFFICE.

JOHN NELSON, OF OTTAWA, KANSAS.

SHOCK ABSORBER FOR RAILROAD CROSSINGS.

Application filed March 12, 1923. Serial No. 624,422.

To all whom it may concern:

Be it known that I, JOHN NELSON, a citizen of the United States of America, residing at Ottawa, in the county of Franklin 5 and State of Kansas, have invented certain new and useful Improvements in Shock Absorbers for Railroad Crossings, of which the following is a specification.

This invention relates to new and useful 10 improvements in shock absorbers for railroad crossings.

An important object of this invention is to provide a device of the above mentioned character that is adapted for overcoming the 15 noise caused by the vibration and jar of a train or street car passing over a frog or crossing.

A further object of the invention is to provide an improved form of cross plate or 20 bridge for accomplishing this purpose.

Other objects and advantages of the invention will be apparent during the course of the following description.

In the accompanying drawing forming a 25 part of this specification and in which like numerals are employed to designate like parts throughout the same,

Figure 1 is a side elevational view, partly 30 in section and partly broken away, of a track crossing with this improved form of crossing plate or bridge in position thereon with a pair of car wheels resting upon the said cross plate or bridge,

Figure 2 is a top plan view of the device 35 shown in Fig. 1,

Figure 3 is a longitudinal sectional view through one of the pairs of cross arms forming part of the cross plate or bridge embodying this invention.

Figure 4 is a perspective view of the cross 40 plate or bridge embodying this invention,

Figure 5 is a fragmentary top plan view of a modified form of the cross plate or bridge,

Figure 6 is a fragmentary top plan view 45 of a further modified form of the invention, and

Figure 7 is a vertical sectional view of the modified form shown in Fig. 6.

In the accompanying drawing, wherein 50 for the purpose of illustration is shown a preferred embodiment of this invention, the numeral 5 designates a car axle carrying the car wheels 6 properly positioned thereupon, the said car wheels comprising the usual tread portions 7 and perpendicular

flanges 8. The intersection of crossing tracks formed by the rails 9 and 10 are formed with the usual neck portion 11 and channel or groove 12.

Referring particularly to Figs. 1 to 4 inclusive there is shown what I have termed as a cross plate or bridge that is constructed of any suitable resilient material and is cut or molded into the form of a cross that consists of the intersecting point 13 and laterally extending arms 14. These arms are provided, in their upper face, with longitudinally extending grooves 15 that intersect at the point of intersection 13 formed by the said arms, there being further provided a single reinforcing wire 16 for adding strength to the said cross plate or bridge. The wire 16 is suitably embedded substantially within the central 55 portion of the arms 14 and extending longitudinally thereof. This cross plate or bridge is adapted to be positioned within the channels or grooves 12 formed by the intersecting portions of rails 9 and 10 and are adapted for being engaged or traveled over by the perpendicular flange 8 formed upon the car wheels 6 for raising the tread portions 7 of the said wheels off of the heads 11 of the tracks thereby overcoming 60 the vibration and jar caused by the said wheels passing over the grooves or channel 12 formed in the track extending at right angles to the track being traversed upon by the said car wheels.

Referring particularly to Fig. 5 where there is shown a modified form of the cross plate or bridge which, however, employs identically the same general formation which consists of the intersecting point 13, 65 laterally extending arms 14, and grooves 15. This form of the invention employs as a reinforcing means the series of three spaced wires 16^a that extend longitudinally of the arms 14 and are properly embedded 70 therein.

Referring particularly to Figs. 6 and 7 wherein there is shown a further modified form of the cross plate or bridge which employs a series of three longitudinally extending reinforcing wires 17 that are embedded within the arms 14. There is further provided as a reinforcing means or wear-reducer relatively small strands of wire 18 that are embedded perpendicularly in the 75 arms 14 and extend between the longitudinally extending reinforcing wires 17

and the surface of the grooves 15. It is to be understood that I do not intend to limit the exact arrangement of these strands of wires 18 in respect to the angle formed by them and the longitudinally extending wires 17.

It is believed that the above description, when taken in connection with the accompanying drawing, will sufficiently explain the construction and operation of the various forms of my invention and that no further description is deemed necessary.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. The combination with a railroad track crossing or frog, of a groove filling bridge, and reinforcing means for said bridge.
2. The combination with a railroad track crossing or frog, of a groove filling bridge and reinforcing means embedded within said bridge.
3. The combination with a railroad track crossing or frog, of a groove filling bridge formed of resilient material, and reinforcing means for said bridge.

4. The combination with a railroad track crossing or frog, of a groove filling bridge resembling a cross, and reinforcing means for the arms of said cross.

5. The combination with a railroad track crossing or frog, of a groove filling bridge resembling a cross, and reinforcing means embedded within the arms of said cross.

6. The combination with a railroad track crossing or frog, of a groove filling bridge resembling a cross, and reinforcing wires embedded within the arms of said cross.

7. The combination with a railroad track crossing or frog, of a groove filling bridge resembling a cross, and reinforcing wire embedded within the arms of said cross and extending longitudinally thereof.

8. The combination with a railroad track crossing or frog, of a groove filling bridge resembling a cross, reinforcing wires embedded within the arms of said cross extending longitudinally thereof, and wear-reducing means carried by said arms.

9. The combination with a railroad track crossing or frog, of a groove filling bridge resembling a cross, reinforcing wires embedded within the arms of said cross extending longitudinally thereof, and perpendicular wear-reducing wires embedded within said arms.

In testimony whereof I affix my signature.

JOHN NELSON.
